UNITED STATES PATENT OFFICE

EARL P. WETMORE, OF CONCORD, MICHIGAN, ASSIGNOR TO THE ANOILCOAL BURNER CO., OF TOLEDO, OHIO, A CORPORATION OF DELAWARE

METHOD AND APPARATUS FOR BURNING FUELS

Application filed October 23, 1924. Serial No. 745,308.

This invention relates to a method and apparatus for burning fuel, and, more particularly, to a burner adapted to form a readily combustible suspension in air of fuels of a semi-fluid nature, such as the stiff pastes formed of solid and liquid fuels, or of other plastic fuels of similar nature.

Composite fuels of this type are commonly formed of minute particles of powdered fuel, from which the ash content may have been removed to a greater or less extent, and of a liquid fuel which surrounds the particles with a film or layer of oil and serves to unite the particles into a coherent paste, 15 of a nature intermediate that of the solid and liquid fuels of which it is composed, and having characteristics different from its constituents. These pastes, the stiffness of which is dependent on the proportions and 20 characteristics of their constituents, may be burned in the manner of solid fuels, but, because of the greater flexibility of control and ease of burning and consequently greater efficiencies in combustion, it is highly desirable to burn them in the manner of fluid fuels by atomizing and diffusing them into a current of air in such a manner that they may be readily ignited and burned in a flame. Owing to the physical characteristics 25 of the composite fuels of the above mentioned types, they can not be handled in quite the same manner as liquid fuels, which flow readily, can be projected in jet form, and are readily broken up to a mist, nor in 30 the manner of powdered fuels, which are already in a fine state of division and partly mixed with air.

An object of my present invention is to provide a method and apparatus which will 40 enable fuels of the above types and characteristics to be burned in a flame in a manner similar to fluid fuels.

Another object of the invention is to provide an apparatus by which the supply of 45 air for supporting the combustion of the fuel may be readily controlled and adjusted to the requirements of the fuel.

A further object of the invention is to provide a fuel burner of the type indicated 50 in which the supply of air to the fuel is au-

tomatically controlled or regulated in accordance with the requirements of the fuel.

A still further object of the invention is to provide an apparatus for burning fuels of the character indicated above in which 55 the fuel is fed in a continuous and positive manner and reduced to a fine state of division and suspension in air.

With these and other objects in view, which may be perceived from the further 60 and detailed description of the invention, the invention comprises the method and apparatus described and set forth in the following specification and claims.

The various features of the invention are 65 illustrated in the accompanying drawings, in which:

Fig. 1 is a side elevation view of a burner embodying a preferred form of my invention, and 70

Fig. 2 is a sectional view of the burner, taken on line 2-2 of Fig. 1.

In my present invention, the fuel is forced in a continuous manner through a supply passage-way by a suitable conveyor means, such as a screw conveyor, and is forced through a narrow orifice to issue as a thin sheet or ribbon. A jet of fluid, preferably air, is directed across the path of the sheet of fuel as it issues from the orifice and closely adjacent the outer face of the orifice so that the front, advancing edge of the sheet of fuel is sheared off and carried into the jet, the pressure of the air and velocity of the jet being sufficient to thoroughly disintegrate the body of fuel and carry the separated particles with their films of oil in a fine suspension in the current of air. The issuing ribbon of fuel is preferably annular in shape and the jet of air is directed outwardly from the interior of the annular ribbon at a right angle to the path of travel of the fuel. The jet, with the finely divided particles carried in suspension is then deflected inwardly and through a nozzle to any suitable combustion chamber, additional or secondary air being supplied, when necessary, to provide sufficient oxygen for complete combustion.

Referring more particularly to the ac- 100

companying drawings, a supply of fuel is placed in a hopper 10 mounted on, and opening downwardly into a horizontal conveyor tube 11, the adjacent end of the tube being closed by a plate 12 secured to the end of the tube wall by screws 13. The fuel falling into the end portion of the tube 11 from the hopper 10 is conveyed forwardly therein by means of a screw conveyor 14 rigidly mounted on a hollow supporting shaft or tube 15 one end of which projects outwardly through, and is supported, in the plate 12. The shaft 15 and conveyor 14 may be driven by any suitable means, such as a worm 16 and gear 17 mounted on the end of the shaft projecting on the outside of the plate 12.

The opposite, inner end of the shaft 15 is supported on a fixed pipe 18, which extends through the shaft 15 and is mounted at its inner end in a support 19 which is spaced and supported from the inner wall of the tube 11 by radially projecting arms 20. The walls of the support 19 at the end of the conveyor 14 are flared outwardly at 21 in a cone shape 25 and extend to within a short distance of the inner face of the wall of the tube 11 leaving a small annular orifice 22. The fuel is forced by the conveyor 14 against the wall 21 of the support 19, which acts as a mandrel or triblet, and through the annular orifice 22, issuing from the orifice as a thin annular sheet.

Air under high pressure for disintegrating the fuel as it issues from the orifice 22, is supplied through the tube or pipe 18, which projects through the triblet or support 19 and extends forwardly thereof for a short distance. The air from the pipe 18 is received within a hollow cone 23 mounted on the projecting end portion of the pipe 18 and having a base wall 24 spaced from the front face of the triblet 19 to provide a narrow or thin space 25 therebetween. From the interior of the cone 23, the air is delivered through openings 26 in the base wall 24 to the space 25 and then flows radially outwardly across the path of the fuel issuing through the orifice 22. The air is supplied under a pressure sufficiently high to disintegrate the sheet or wall of fuel as said air cuts across the path of the fuel and carry particles of disintegrated fuel with it, a pressure of from fifty to one hundred and fifty pounds being usually sufficient for this purpose.

The jet of air and commingled fuel is received and deflected in an annular space 27 formed between the cone 23 and the inner face of a curved annular wall 28 mounted by means of a flange 29 on a flange 30 on the front end of the tube 11. The inner face of the wall 28 is curved or bulged outwardly about the edge of the cone, which is rounded as at 31, to give the outwardly flowing jet 65 of air a curved, expanding path, bringing it

to the converging face of the cone 23 and thus giving it a forward velocity as it expands.

As the mixture of air and suspended fuel flows towards the tip of the cone 23, it enters a nozzle member 32 mounted by means of an outward flange 33 on a flange 34 of the wall 28, said nozzle member 32 having a contracted or Venturi portion 35 into which the jet of air is directed on leaving the cone 23, and, extending therefrom, an expanding mouth portion or combustion chamber 36 which is directed towards the mouth of a furnace in which the fuel is to be burned. In passing through the contracted portion of the venturi, a slight vacuum is created into which an additional amount of air may be drawn through inlet openings 37 provided for this purpose, thus enabling an amount of secondary air to be introduced when required to supply the requirements of the fuel. The amount of additional air thus drawn into the stream of fuel may be regulated by means of a damper ring 38 slidably mounted on a cylindrical surface 39 on the nozzle and adjustable towards or from a conical surface 40 to provide a variable inlet orifice for the secondary air.

The rate of supply of fuel is controlled by the rate at which the screw conveyor 14 is driven from the worm 16 and gear 17, and the supply of air is controlled in accordance with the driving of the worm. Through this apparatus, therefore, the supply of fuel may be accurately controlled and may be quickly adjusted to the demands of the furnace to which the fuel is supplied.

The disintegrating action of the air jet is such that the minute particles of solid fuel are separated from each other and carried in suspension by the air in such a condition that they may be readily ignited and burned similarly to oil or other liquid fuel.

As changes of construction could be made within the scope of my invention, it is desired that all matter contained in the above description or shown in the accompanying drawing shall be interpreted as illustrative and not in a limiting sense.

Having described my invention, what I claim and desire to secure by Letters Patent is:

1. A fuel burner which comprises, a fuel feeding passage-way having an annular outlet orifice, means in said passageway for advancing fuel therethrough and through said outlet orifice, and means for directing a jet of air radially outwardly across the path of the fuel issuing from said orifice to break up and mix said fuel with said air.

2. A fuel burner which comprises, a fuel feeding passageway having an annular outlet orifice, a screw conveyor in said passageway for forcing fuel therethrough and through said outlet orifice, and means for

supplying air under pressure through said screw conveyor and directing a jet of said air radially outwardly against the fuel issuing from said annular outlet orifice, to disintegrate said fuel and carry it in said air.

3. A fuel burner which comprises, a fuel feeding passage-way having an annular outlet orifice, a screw conveyor in said passage-way for forcing fuel therethrough and through said outlet orifice, means for supplying air under pressure through said screw conveyor and directing a jet of said air radially outwardly against the fuel issuing from said annular outlet orifice, to disintegrate said fuel and carry it suspended in said air, and means for introducing additional quantities of air into said commingled air and fuel and for directing said air and fuel mixture to a furnace.

4. A fuel burner which comprises, a fuel feeding passage-way, an air supply pipe extending through said passage-way, a support for said pipe at the outlet end of said passage-way and forming an annular outlet with the walls of said passage-way, a screw conveyor rotatably mounted on said pipe to force fuel through said orifice, a hollow cone spaced slightly from the outer face of said support to receive air from said pipe and direct it radially outwardly between its base and said support to intersect the fuel issuing through said annular orifice, and a nozzle mounted to receive the commingled air and fuel.

5. A fuel burner which comprises, a fuel conveyor tube, an air supply pipe extending through said tube, a support for said pipe at the outer end of said tube and forming an annular outlet orifice with the walls of said tube, means for conveying fuel through said tube and forcing it through said annular orifice, and means for receiving air from said pipe and directing it radially outwardly across the path of the fuel from said orifice.

6. A fuel burner which comprises, a fuel conveyor tube, an air supply pipe extending through said tube, a support for said pipe at the outer end of said tube and forming an annular outlet orifice with the walls of said tube, a screw conveyor rotatably mounted on said pipe to force fuel through said annular outlet orifice, a hollow cone mounted on the end of said pipe with its base spaced a short distance from said support to form a narrow jet passage intersecting the fuel from said annular orifice, said cone having passages to receive air from said pipe and direct it to said jet passage, and a nozzle member adapted to deflect the air and fuel from said jet and direct them to a furnace.

7. A fuel burner which comprises, a fuel conveyor tube, an air supply pipe extending through said tube, a support for said

pipe at the outer end of said tube and forming an annular outlet orifice with the walls of said tube, a screw conveyor rotatably mounted on said pipe to force fuel through said annular outlet orifice, a hollow cone mounted on the end of said pipe with its base spaced a short distance from said support to form a narrow jet passage intersecting the fuel from said annular orifice, and to receive air from said pipe and direct it to said jet passage, a nozzle member positioned to deflect the air and fuel from said jet and direct them to a furnace and means for admitting additional regulated quantities of air to said nozzle.

In testimony whereof, I affix my signature.

EARL P. WETMORE.
